REMOTE CONTROL SYSTEM

George W. Baughman, Pittsburgh, Pa., assignor
to The Union Switch & Signal Company, Swiss-
vale, Pa., a corporation of Pennsylvania

Application January 16, 1940, Serial No. 314,125

23 Claims. (Cl. 179—3)

My invention relates to remote control systems, and more particularly, to the communication or line circuits for centralized traffic control systems for railroads, in which a train dispatcher's office or other suitable point of control is connected with a plurality of field stations by line wires, over which impulse codes of signals are transmitted at times for controlling selected devices at the stations, and at other times for indicating the condition of station devices at the office.

My invention is an improvement upon the system disclosed in the copending application Serial No. 600,786, filed March 23, 1932, by L. V. Lewis, for Remote control systems, which corresponds with British Patent No. 415,787, issued September 3, 1934, upon those disclosed in applications Serial Nos. 222,860, filed August 3, 1933, and 223,287, filed August 5, 1933, by C. S. Snavely and A. B. Miller, for Remote control systems, upon that disclosed in application Serial No. 261,241, filed March 11, 1939, by L. V. Lewis, for Remote control systems, and upon that disclosed in my application, Serial No. 256,976, filed February 17, 1939, for Remote control system.

Since a dispatcher's telephone circuit is generally required in connection with systems of this character, it is often desirable to provide additional communication channels over the line wires of the centralized traffic control system for telephone or telegraph communication, and to also arrange the apparatus so as to permit the use of the line wires by another code system employing different codes, such as a dispatcher's telephone selector system, without interference, even though two or more codes are initiated simultaneously.

In order to use the line wires more efficiently, the dispatcher's telephone circuits are usually "simplex," that is, are so arranged that the two line wires in multiple, with ground return, provide a telegraph circuit over which telegraph communication may be effected in both directions, without interference with the use of the line wires in series for telephone or code signaling purposes. Heretofore it has not been practicable to superimpose a telegraph circuit in this manner upon the line circuit of a central battery centralized traffic control system, such, for example, as that shown in my prior application hereinbefore referred to, because the station apparatus is ordinarily connected to the line wires in series and the continuity of the line wires is at times interrupted by the transmitting contacts at the field stations. Nevertheless, the C. T. C.

circuit energized from a central battery at the control office is often preferred over the alternative "bridged" line circuit as used heretofore in certain remote control systems, for the reason that sources of line current at the field stations are not required.

One object of the present invention is the provision of novel circuit arrangements for a central battery C. T. C. system, by means of which impulse codes may be transmitted from a control office to various field stations and from the stations to the office, over line wires arranged to provide at substantially all times an uninterrupted metallic circuit from end to end, which may be used for telephone and telegraph purposes, without interference. These arrangements include means for signaling in one direction over the line wires by periodically disconnecting the source of current by which the line wires are normally energized at one end, and for signaling in the opposite direction by periodically connecting the line wires together through a suitable impedance, at the opposite end of the line or at an intermediate point, to vary the current supplied by said source.

Another object of my invention is the provision of a system in which current of one polarity is used for the transmission of control codes from the office, and the opposite polarity is used both for the transmission of indication codes from the stations and of selector codes from the office, without interference.

Another object is the provision of an improved lockout circuit for insuring that when two or more transmitters initiate codes at the same time the codes will be transmitted one at a time in order without interference. A feature of this circuit is the provision of means for stopping each station transmitter after having transmitted the first impulse of a code until a return impulse is received from the office of a character indicating that the office apparatus is in condition to receive the code.

Still another feature of my invention is the provision of a Wheatstone bridge circuit at each station which is formed by the operation of the station transmitter, and which is effective to reduce the potential difference across the line wires extending to stations more remote from the office substantially to zero while maintaining a substantial potential difference across the line wires extending toward the office to effect the selective energization of relays at the stations in accordance with their relative locations with respect to the office.

Other objects, purposes and features of my invention will be pointed out as the description proceeds.

I shall describe one form of apparatus embodying my invention, and shall then point out the novel features thereof in claims.

In the specific embodiment of my invention illustrated in the accompanying drawing, it is to be understood that the centralized traffic control system chosen to illustrate my invention is the "Time code" system of the Lewis application, Serial No. 600,786, corresponding to British Patent No. 415,787, while the selector system is that of the Field Patent No. 1,343,256, granted June 15, 1920, each of which systems as herein disclosed having been modified in certain respects in accordance with the requirements of my invention as will hereinafter be pointed out.

To facilitate an understanding of my invention I have designated those elements of the C. T. C. system shown in the accompanying drawing which are similar to corresponding elements of the system of the Lewis British patent, such as the master relays M, the transmitter relays T, the slow-acting relays L, etc. by the same reference characters as employed in that patent, and likewise in respect to the selector system shown herein, it is to be understood that the code wheel 89, contacts 96 and 97, relays 86 and 87, and the selector 72 are similar to the correspondingly designated devices of the Field patent referred to.

As explained in the British patent, the reference characters Y and Z designate the line wires of the system which extend from the point of control, usually a train dispatcher's office, as indicated by the legend "Office" on the drawing, through each of a plurality of field stations of the C. T. C. and selector systems in turn, the successive sections of the line being distinguished by numerical suffixes. Since the C. T. C. field stations are generally similar, and since the selector locations are also similar one to another, only one of each is shown in order to simplify the drawing. The line wires Y and Z are included in a normally closed line circuit energized from a central battery 80 at the office which includes the normally closed contacts of a transmitter relay OT and the windings of two line relays ORC and ORI at the office, the winding of a line relay RC at each C. T. C. field station and the winding of a line relay SR at each selector location. The line relays shown herein are to be understood to be of a sensitive biased polar type each having two balanced line windings of relatively low impedance such as are employed in the system of my prior application, Serial No. 256,976, while relays ORC and ORI each have, in addition, a third winding by means of which they may be biased electrically and thereby rendered responsive to variations in the strength of line current of the proper polarity.

Each line relay is biased to the right, as indicated conventionally by a tension spring attached to its armature, and therefore closes its right-hand contacts when deenergized, and it is to be understood that each line relay is so polarized that the flow of current through any one of its windings when the positive terminal of the source is connected to the left-hand terminal of the winding will operate the armature in opposition to the bias to cause the left-hand contacts to be closed. The direction of the current normally flowing through the windings is indicated by arrows on the drawing.

This normally closed C. T. C. line circuit as shown in the drawing may be traced from the upper or positive terminal of battery 80, resistor 5, contact 6 of transmitter relay OT, normal contact 7 of a stick polar relay PC, back contact 8 of relay 86, through the upper windings of a low-pass filter comprising coils 9 and condensers 10, the upper windings of relays ORC and ORI to line Y, thence over back contact 30 of relay 10 through the upper winding of relay RC to the line wire sections Y1 and Y2, the upper winding of relay SR, line wire Y3, the upper winding of a telephone transformer or repeating coil 11, resistor 12 to wire X1. From this point the current 15 returns to the lower terminal of battery 80 over a precisely similar path which as will be clear from the drawing includes resistor 13, the lower windings of the repeating coil 11 and of the line relays, the several sections of line Z, and contacts 14, 15 and 16a of relays 86, PS and OT. Relay RC is normally energized, as shown, like the station line relay R of the British patent hereinbelow referred to, and functions like that relay to hold the station coding unit of the C. T. C. system in its normal inactive condition.

The office line relay ORC, however, occupies its deenergized position because the effect of the line current is balanced or neutralized by an opposing current flowing from the upper terminal of battery 80, resistor 5, resistor or artificial line 19, back contact 20 of relay OM, through the middle or local windings of relays ORI and ORC to the lower terminal of battery 80. Relays ORI and SR normally are held in their deenergized positions 30 by the reverse current in their windings as well as by their bias. The station line relays RI are normally deenergized.

The office coding unit is controlled by one or the other of the two line relays ORC and ORI, dependent upon the position of relay OM, over two wires 17 and 18 which correspond to the two wires leading to terminal B of a source of current over the front and back contacts, respectively, of the office line relay OR of the British patent.

The circuits by which the timing relays OL1, OL2, etc., are controlled over wires 17 and 18 are similar to the corresponding circuits shown in the patent, being reproduced herein merely for convenience. This is also true of the station circuits for controlling the relays L1, L2, etc. As shown herein, terminal B of the local source is normally connected to wire 17 over back contact 21 of relay OM and right-hand contact 22 of relay ORI. The office coding unit is therefore held normally in its inactive condition as in the system of the patent.

The C. T. C. and selector systems are interlocked so that but one can obtain the use of the line at a time, by including back contacts of relays of each system, which open when the system is in use, in the starting circuits for the other system, as will hereinafter be explained.

I shall now describe the operation of the C. T. C. system in detail, first explaining the transmission of a control code from the office, and then the transmission of an indication code from a field station. The operation of the selector system will then be described, and finally the operation of the superimposed telephone and telegraph circuits will be explained.

With the selector system in its normal inactive condition, as shown, it will be assumed that the operator initiates a C. T. C. control code by positioning suitable control levers and then picking up a start relay to energize the master relay

OM as explained in the Lewis British patent. The picking up of a relay "start" as shown herein completes a pick-up circuit at its contact 23 for relay OM, which circuit, as in the patent, includes back contacts b of the slow-acting relays OL1 or OL2, one or the other of which is energized when the line is in use, the circuit as shown herein extending to terminal B of the local source at back contact 24 of relay 86. Relay OM therefore picks up, and by opening contact 20 interrupts the circuit through the local windings of the line relays ORC and ORL. The direction of current through the line winding of relay ORL is such that this relay remains in its deenergized position as shown, but relay ORC is now conditioned to respond to the normal line current and therefore operates its contact 25 to the left. Contacts 21, 26 and 27 of relay OM operate to transfer the control of the office coding unit from relay ORL to ORC, wire 17 now being energized from terminal B over the front or left-hand contact 25 of relay ORC and front contact 26 of relay OM, and wire 18 becoming energized over right-hand contact 25 whenever relay ORC is released during the transmission of the control code. The condition of the apparatus controlled over wires 17 and 18 is now precisely as in the system of the British patent hereinbefore referred to, and therefore operates as therein described. For an understanding of my invention it is believed sufficient to point out that relay OT operates intermittently to deliver a code of impulses and intervals of selected lengths to the line to which relays ORC at the office and relay RC at each C. T. C. station respond. The coding apparatus responds selectively to pick up a selector relay such as relay 234S at the office and a selector relay S at the corresponding station in accordance with the character of a first portion of the code, and then other relays controlled by relay S are governed in accordance with the positions of control levers associated with relay 234S. The first interruption of the line circuit completes a pick-up circuit from terminal B over the right-hand contact 25 of relay ORC and front contact 21 of relay OM, wire 18, back contact d of relay OLEP, back contact f of relay OL2, back contact b of relay OLBP, relay OL1 to terminal C, so that relay OL1 picks up, closing a branch circuit over its contact a from wire 18 through relay OL2 to terminal C so that relay OL2 picks up. The closing of contacts c of relays OL1 and OL2 completes a circuit for relay OLB, which picks up, closing in turn its contact c to pick up relay OLBP. The latter relay, at its contact b, transfers the control of relay OL1 to wire 17 so that, during the transmission of the code, relay OL1 is energized each time relay ORC picks up, and relay OL2 is energized each time relay ORC releases. If the line fails and remains open during transmission, it will be seen that relays OL1, OLB and OLBP will release successively, relay OLB at its contact a opening the stick circuit including the winding and front contact a of relay OM by which relay OM is held energized to maintain the transmitter in operation, but relay OL2 will be held energized over wire 18 and its front contact a. It follows that if the line fails, transmission is stopped, and that the starting circuit does not become available until the line is again restored, all of which is precisely as described in the British patent.

At the end of the control code, the operation of relay OT ceases and the line becomes steadily energized, whereupon relays OL2, OLB,

OM, OLBP and OL1 release successively, in that order. Relay OM upon releasing transfers the connection from terminal B to wire 17 over the front contact of relay ORC to the branch circuit including the right-hand or back contact 22 of relay ORL, and by closing contact 20 reenergizes the local windings of the office line relays, so that relay ORC becoming balanced, assumes its deenergized position, thereby restoring the apparatus to its normal condition, as shown.

At the field station, wire 73 corresponding to the office wire 17 is normally energized from terminal B, back contact 28 of an added auxiliary relay MP, and the front or left-hand contact 29 of relay RC. When relay RC is released, wire 77 corresponding to the office wire 18 is energized over the back or right-hand contact 29 of relay RC. Since relay RC is in series with relay ORC, it will be seen that wires 13 and 77 are energized in unison with wires 17 and 18 of the office coding unit and therefore the station slow acting relays L1, L2, LB and LEP are each operated in unison with the corresponding office relay and that the station apparatus will selectively receive the control code as described in the British patent.

I shall next assume that a station device having indications to transmit changes its condition thereby energizing the station starting relay ST. 30 When the line assumes its normal condition after the transmission of the control code as already described, relays L2 and L1 release, and a starting circuit is completed from terminal B at contact c of relay ST as described in the patent to 35 pick up relay M, which in turn picks up relay T to initiate the first step of an indication code.

In the system of the patent, relay T operates like relay OT already described to open the line circuit, but as disclosed herein, the transmission 40 is effected in a novel manner which maintains the continuity of the line wires from one end of the line to the other, thereby avoiding interference with the telephone or telegraph circuits. When relay T picks up, the line wires Y and Z are connected together through the windings of 45 relays RI and RC, in such a manner as to form a Wheatstone bridge comprising two branches each shunting the wires Y and Z but so balanced that wires Y1 and Z1 leading to more remote stations 50 are brought to the same potential, thereby reducing the current in the portion of the line circuit extending to the more remote stations substantially to zero. This portion of the line circuit includes resistors 12 and 13 which are 55 customarily of 500 or 1000 ohms each and its resistance is relatively high in comparison with that of relays RI and RC, which are normally 5 or 10 ohms per winding. It follows that due to the shunt paths provided through relays RI and 60 RC when relay T is picked up, the resistance of the remaining portion of the line circuit is substantially reduced, thereby increasing the current through the office line relays, so that relay ORC picks up.

65 One branch of the Wheatstone bridge referred to may be traced from wire Y, front contact 30 of relay T, the upper winding of relay RI, the right-hand winding of the choke coil 31, to wire Z1, and from wire Z1 through the lower winding 70 of relay RC, resistor or artificial line 32 to wire Z. The other branch of the bridge may be traced from wire Y, resistor or artificial line 33, the upper winding of relay RC to wire Y1, and from wire Y1 through the left-hand winding of coil 75 31 and the lower winding of relay RI, front con-

tact 34 of relay T to wire Z. Since the two branches include similar elements, it is evident they may readily be balanced to bring points Y1 and Z1 to the same potential. It will also be seen that the shunt paths from wire Y to wire Z have the characteristics of a low pass filter such as the one comprising the coils 9 and condensers 10 at the office, since they include the series coils 31 and shunt elements comprising the condensers 35 in the line and the condensers 36 bridging the contacts of relay T.

In the system of the British patent, the first step of an indication code is a short line open step, while the first step of a control code is made relatively long in order to give precedence to the control code in the event the office and one or more stations initiate codes at the same time. In accordance with my invention this differentiation is obtained in a different manner, consequently, the station transmitter T may be arranged to function on the first step in the same manner as the office transmitter OT. It is therefore to be understood that relay T remains picked up on the first step for a relatively long time interval. The line relays RC at the more remote stations therefore receive a long "line open" code step due to wires Y1 and Z1 being held at the same potential by relay T at the transmitting station, the same as when a control code is being received, and the relay E of the station coding unit which responds selectively to a long first step picks up at each of these more remote stations to open at its contact a the energizing circuits for the associated relay M, just as when the line is "sectionalized" as occurs under corresponding conditions in the line circuit of the patent.

It will be clear therefore, that when indication codes are initiated by two or more stations at the same time, the station nearest the office retains sole control of the line, as heretofore.

When the office line relay ORC picks up due to the increase in line current produced by the station relay T, it completes a circuit from terminal B at its left-hand contact 25, back contact 26 of relay OM, back contact 37 of relay OLBP, the upper winding of relay PC to terminal C. Relay PC is a polar relay of the magnetic stick type and now operates its contacts 7 and 15 to the left, to reverse the polarity of the current supplied by battery 80 to the line circuit, and removing relay OT from control of the line.

At the transmitting station, due to the reversal of the polarity of the line current, relay RI picks up and relay RC releases, completing a circuit from terminal B over contacts 38, 39 and 40 of relays RI, RC and M, through relay MP to terminal C, and relay MP picks up to complete a stick circuit extending to terminal B at its front contact 41.

The station coding apparatus at the transmitting station does not respond to the initial energization of relay T but is held in its normal inactive condition until relay RC releases, whereupon wire 73 is deenergized and wire 77 becomes energized over the right-hand contact 29 of relay RC, and as soon as relay MP picks up, contact 29 is disconnected and terminal B is connected to wire 77 over front contacts 28 and 42 of relays MP and RI. Relay MP opens contact 43 in the 70 circuit for relay E, so that relay E remains deenergized at the transmitting station.

It will be seen that if the office and one or more stations are conditioned to start transmission at substantially the same time, the station 75

nearest the office will retain control of the line only if it succeeds in reversing relay PC, and otherwise the office will retain control of the line, but in any case the selection is obtained in a positive manner because it depends merely upon the position of relay PC. In the event relay OM picks up, relay PC will fail to reverse in response to the initial energization of the station transmitter relay T, and the opening of the line circuit by the office transmitter OT will release relay RC without energizing relay RI thereby energizing wire 77 and eventually picking up relay E at the transmitting station to release relay M at that station. It will be seen that under these circumstances the system functions precisely as when the line circuit of the patent is used, in that all the stations are conditioned to receive the control code.

Assuming that a field station retains control of the line, when the line polarity is reversed by relay PC, the office line relay ORC releases and relay ORI picks up to close its left-hand contact 22. The balance due to the current through the local windings of these relays which with normal polarity is effective to govern relay ORC is now effective to govern relay ORI, which therefore picks up when relay T picks up to shunt the line wires through relays RI and RC as hereinbefore described.

It follows that relays ORI and RI pick up on each odd numbered step of the code, when relay T is picked up, and release on each even numbered step, when relay T releases. In other words, in an indication code, the increase in line current, due to the shunt applied to the line at the transmitting station for energizing relays ORI and RI, corresponds to a "line open" step of a control code, and the restoration of the line to normal by removing the shunt to release relays ORI and RI, to a "line closed" step of a control code.

It will be evident without further explanation that the continued operation of relay T will result in the proper transmission of an indication code. As described in the British patent, relay O16 at the office, and relay 16 at the station, become energized on the sixteenth or final step of an indication code. Relay 16 by opening its front contact c releases relay M to stop the operation of relay T, while relay O16, as shown herein, closes a contact 44 to momentarily energize the lower winding of relay PC in such a direction as to cause contacts 7 and 15 to move to the right, thereby restoring the line circuit to normal. At this time, relay T is deenergized, consequently ORI is balanced and relay ORC energized in such a direction as to close its right-hand contact 25. Consequently both these relays occupy their normal positions as shown in the drawing and remain in that position after the line polarity is restored to normal. At the transmitting station, relay RI is deenergized and relay RC energized in such a direction as to close its right hand contacts 29 and 39, relay RC having been held in that position for the duration of the indication code. When the line polarity is restored to normal, relay RI being disconnected remains deenergized but relay RC picks up closing its left-hand contacts 29 and 39. When relay M releases on the last step, the release of relay MP follows, transferring the energization of wire 73 from contact 42 to contact 29 so that wire 73 remains energized. Then relays L2, LB, LBP, 16 and L1 release successively in that order, completing the restoration of the station apparatus to normal.

The selector transmitting apparatus, as explained in the Field patent, comprises a plurality of code wheels 89, one for each selector, of which but one is shown herein, each of which when wound up and released makes one revolution during which a connecting relay 86 is energized to permit a code transmitter relay 87 to function. As the code wheel rotates, relay 87 is intermittently energized over a circuit including the code wheel contacts 96 and 97 in accordance with the arrangement of the code wheel teeth, to deliver a code of direct current impulses, all of which are of the reverse polarity, to the line wires Y and Z for operating the line relays SR.

As disclosed herein, the apparatus is arranged so that the operation of a code wheel is ineffective unless it is released when the line is available, as manifested by the deenergized condition of the relays OM, OL2 and OL1 of the C. T. C. office coding unit. When these relays are all deenergized, the release of a code wheel completes a circuit from terminal B over the back contacts 45, 46 and 47 of these relays, back contact 48 of relay 86, code wheel 89, contact 96 and relay 86 to terminal C. Relay 86 picks up to connect the line wires Z and Y to battery 80 over its front contacts 14 and 8, and contacts 3 and 4 of relay 87, and at its front contact 49 completes a stick circuit for itself which is independent of the relays OM, OL2 and OL1 and which is opened at contact 96 when the code wheel 89 completes its revolution. The circuit for intermittently energizing the code transmitter relay 87 extends from terminal B, contacts 49 and 48, code wheel 89, contacts 96 and 97, relay 87 to terminal C.

It is to be noted that as shown herein relay 87 has front contacts only, and that the selector codes include impulses of only one polarity while in the Field patent it is employed as a pole-changer to deliver impulses of alternately opposite polarity to the selectors 12, these being bridged directly across the line in series with a condenser 74. As shown herein each selector 72 is energized through its condenser 74, by impulses of alternately opposite polarity generated locally in response to the operation of its associated line relay SR, as will be apparent from the drawing.

During the transmission of a selector code by relay 87, the C. T. C. office transmitter is prevented from functioning because the pick-up circuit for relay OM is held open at back contact 24 of relay 86. Since the selector code impulses are all of the reverse polarity, it is evident that the C. T. C. station relays RC will remain in their deenergized position. Each relay L2 is therefore held energized over wire 77 and its front contact a, and holds its back contact b open in the pick-up circuit for the associated relay M to prevent the station transmitter from functioning. At the office, relays ORC and OR1 remain in their deenergized positions during the transmission of the selector codes, and it follows that the C. T. C. receivers at the office and stations are wholly non-responsive to the selector codes.

It will be evident that the selector line relays SR are non-responsive to control codes, and are also non-responsive to indication codes provided the relay SR is located between the office and the transmitting station, and will respond to an indication code only when located at a point more remote from the office. It is however, impossible to operate any selector by a C. T. C. code because of the difference in code

character. As described in the Field patent, the selector code includes two long steps in a code of 32 steps or less, the total number of steps chosen for illustration being 15, although in present day practice, a total of 17 or 27 steps is generally used. The selectors are immune to the C. T. C. codes because the latter codes always contain at least three long steps and the number of short impulses in any 17 consecutive steps is insufficient to advance a selector to the point required to close its final contact. It follows that the total number of codes provided by both systems may be used without interference.

As hereinbefore mentioned, the line wires Y and Z provide a non-interfering telephone circuit which as shown extends from the telephone apparatus 50 at the office through a high-pass filter illustrated as the condensers 51 to line wires Y and Z, thence from station to station through the by-pass condensers 35 bridging the line relays RC and condensers 52 bridging the line relays SR, and through the repeating coil 11 to the telephone apparatus 53 at the distant end of the line.

At the office, the C. T. C. and selector apparatus are connected to the line wires Y and Z through a conventional low-pass filter corresponding to that of the Field patent and comprising coils 9 and condensers 10, which effectively prevents the shunting of the telephone currents through battery 80, and at the same time limits the rate of change of the code signaling currents to render the control and selector codes substantially inaudible in the telephones. The coils 31 prevent the shunting of the telephone current when the line is bridged at a station, and together with condensers 35 and 36 are effective to render the indication codes inaudible.

The telegraph circuit as shown herein includes, at each end, the usual duplex apparatus as ordinarily used for Morse or printer operation, comprising circuits at each end of the line extending from ground through a current source NI or BI, the contacts of a pole-changer relay 45 PC1, and the balanced windings of a line relay R1 to line X or XI and through an artificial line AL to ground. The line wires Y and Z complete a metallic connection between wires X and XI by the provision of the usual simplex connection at 50 each end. As illustrated, wire X is connected to wires Y and Z at one end of the line through resistors 54 and 55, the coils 9 and the windings of the office line relays, while wire XI is connected to Y and Z at the other end of the line through resistors 12 and 13 and the repeating coil 11. Since the telegraph currents in line wires Y and Z flow in opposite directions through the windings of the line relays they are without effect upon the C. T. C. or selector systems, and it is also obvious that the resistors 12, 13, 54 and 55 may be readily balanced so that no current from battery 80 flows through the telegraph relays R1. The two windings of each of the filter coils 9 and 31 are preferably closely coupled so as to present the minimum impedance to the telegraph currents flowing in opposite directions through these windings. The telegraph circuit moreover is not effected by the operation of the station transmitter T. Normally, the telegraph currents pass from wires Y and Z to wires Y1 and Z1 over the back contacts 30 and 34 of relay T and the windings of relay RC. When relay T is energized, however, resistors 32 and 33 are included in series with the windings of relay RC but at the same time, multiple paths are com-

pleted from wires Y and Z over the front contacts 30 and 34 and the windings of relay RI and coil 31 to wires Z! and Y!, respectively, so that when the bridge which these circuits form is balanced the resistance with respect to the telegraph currents is the same with relay T picked up as when relay T is released, and the transmission of indication codes is therefore without effect upon the telegraph circuit.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a remote control system, an office and a station connected by two line wires, a normally closed signaling circuit including said line wires and a source of current, line relay means at the office responsive to a substantial increase in current in said line circuit, a code transmitter at said station operable to connect said line wires together at the station to increase the current in said line circuit repeatedly in accordance with a code, and a code receiver at the office governed by said line relay means and selectively responsive to said code.

2. In a remote control system, an office and a station connected by two line wires, a normally closed code signaling circuit including a source of current at the office and said line wires in series, a line relay at the office responsive to variations in current in said line circuit, a superimposed signaling circuit including said line wires in multiple, a code transmitter at said station operable to connect said line wires together to vary the current in said normally closed circuit repeatedly in accordance with a code while maintaining the continuity of said superimposed circuit, and code responsive means controlled by said line relay selectively responsive to said code.

3. In a remote control system, an office and a station connected by two line wires arranged to provide a voice frequency communication circuit, a code signaling circuit including said line wires in series and a source of direct current at the office, said source being bridged across said line wires in series with a low-pass filter and a line relay, a code transmitter at said station effective when operated to connect said line wires together through a low-pass filter to vary the direct current flow in said code signaling circuit while maintaining the impedance of said voice frequency circuit substantially unchanged, and code responsive means at the office controlled by said line relay in response to said current variation.

4. In a remote control system, an office and a plurality of stations connected by two line wires, a normally closed code signaling circuit including a source of current at said office, said line wires in series, and a relatively high resistance at the end remote from said office, a line relay at the office responsive to a substantial increase in current in said line circuit, a line relay at each station normally energized by the current in said line circuit, a code transmitter at each station operable repeatedly in accordance with a code and effective when operated to connect said line wires together to increase the current in the line circuit portion between the office and said station and to reduce the current in the remaining portion substantially to zero while maintaining the continuity of said line circuit, code responsive

means at the office selectively controlled by the office line relay, and a starting circuit at each station for initiating the operation of the associated transmitter including a contact which opens if the line relay at such station becomes deenergized.

5. In a remote control system, an office and a station connected by two line wires, a normally closed signaling circuit including a source of current at said office, said line wires, and a relatively high resistance at a point remote from said office; line relay means at the office responsive to a substantial increase in the current in said line circuit, a code transmitter at said station operable

15 to bridge a relatively low resistance across said line wires repeatedly in accordance with a code to govern said line relay means, and a code receiver controlled by said line relay means selectively responsive to said code.

20 6. In a remote control system, an office and a station, a simplex telephone line comprising two line wires connected in series to telephone apparatus and in multiple to telegraph apparatus at each end to provide simultaneously available

25 telephone and telegraph circuits for communication between the two ends of said line, a normally closed code signaling circuit including said line wires in series and a source of direct current at the office, said source being bridged across

30 said line wires in series with a low-pass filter and a line relay balanced with respect to said telegraph circuit, a code transmitter at said station operable to connect the line wires together through a low-pass filter to control the line relay 35 in said code signaling circuit while maintaining the impedance of said telephone circuit and also of said telegraph circuit substantially unchanged, and a code receiver at the office controlled by said line relay.

40 7. In a remote control system, two line wires extending from a central office through an intermediate station to a more distant station, a normally closed code signaling circuit including, in series, a source of current and line relay means

45 at said office, said line wires and a resistance connecting said line wires at said more distant station; a local balancing circuit effective to neutralize the effect upon said line relay means of the current normally flowing in said code signaling circuit, but rendering said line relay means responsive to an increase in said current, a code transmitter at the intermediate station operable

50 to close a relatively low resistance bridge across said line wires repeatedly in accordance with a code to govern said line relay means, and a code receiver controlled by said line relay means selectively responsive to said code.

8. In a remote control system, two line wires extending from a central office through an intermediate station to a more distant station, a normally closed line circuit including in series a source of current at said office, said line wires and a normally energized line relay at each station; line relay means at the office responsive to

65 a substantial increase in the current in said line circuit, a code transmitter at each station effective when operated to shunt said line circuit to increase the current in the portion thereof extending to the office and to decrease the current in the remaining portion substantially to zero, each said transmitter when initiated being operable repeatedly in accordance with a multiple step code to govern said line relay means, a code receiver controlled by said line relay means selectively responsive to said codes, and means for

initiating each code transmitter effective only when the associated line relay has been steadily energized for a predetermined time interval.

9. In a remote control system, two line wires extending from a central office through an intermediate station to a more distant station, a normally closed code signaling circuit including, in series, a source of current at said office, a normally energized line relay at each station, and an impedance bridged across said line wires at the more distant station; a second impedance bridged across said line wires at said office, a superimposed circuit extending from the mid-point of one said impedance to the mid-point of the other and including said line wires in multiple, line relay means at the office responsive to a substantial increase in the current in said code signaling circuit but balanced with respect to said superimposed circuit, a code transmitter at each station effective when operated to complete a Wheatstone bridge circuit forming a shunt effective to increase the current in the portion of the code signaling circuit extending to the office, said bridge being balanced to reduce the current in the remaining portion of said circuit substantially to zero while maintaining the impedance of said superimposed circuit substantially unchanged, each said code transmitter when initiated being operable repeatedly in accordance with a multiple step code to govern said line relay means, a code receiver controlled by said line relay means selectively responsive to said codes, and means for initiating each code transmitter effective only when the associated line relay has been steadily energized for a predetermined time interval.

10. In a remote control system, two line wires extending from a central office through an intermediate station to a more distant station, a normally closed code signaling circuit including, in series, a source of current, line relay means and a code transmitting contact at said office, said line wires, and a line relay at each station, a local balancing circuit effective to neutralize the effect upon said line relay means of the current normally flowing in said signaling circuit, but rendering said line relay means responsive to a substantial increase in said current, means for at times opening said local circuit to render said line relay means responsive to the normal current in said signaling circuit and to initiate the operation of apparatus governed by said line relay means for repeatedly opening said transmitting contact to control said line relay means and said station relays in accordance with different control codes, code receivers controlled by the station line relays selectively responsive to said codes, a code transmitter at each station; means effective to initiate the operation of each code transmitter effective at times provided said line circuit has been in its normal closed condition with said line relay means in its balanced condition for a predetermined time interval, means controlled by each code transmitter when initiated to repeatedly shunt said line wires to increase the normal current in said line circuit to govern said line relay means in accordance with a code, and a code receiver controlled by said line relay means selectively responsive to each such code.

11. In a remote control system, two line wires extending from a central office to a distant station, a normally closed line circuit including, in series, a source of current and a normally closed transmitting contact at said office, said line wires, and a normally energized line relay at said station; line relay means at the office controlled

over said line circuit but normally responsive only to a substantial increase in the normal current in said line circuit, a code transmitter at said station effective when operated to shunt said line circuit to increase the current in the portion thereof extending to the office, said transmitter when initiated being operable repeatedly in accordance with a multiple step code to govern said line relay means, a code receiver controlled by said line relay means selectively responsive to said code, means for initiating said code transmitter effective only when the station line relay is steadily energized, means at the office effective at times for temporarily rendering said line relay means responsive to the normal current in said line circuit and for then operating said transmitting contact to repeatedly interrupt said circuit in accordance with different codes under the control of said line relay means, and a code receiver controlled by the station line relay selectively responsive to said codes.

12. In a remote control system, two line wires extending from a central office to a distant station, a normally closed line circuit including, in series, a source of current of reversible polarity at the office, said line wires, and a normally energized line relay at said station; line relay means at the office controlled over said line circuit but normally responsive only to a substantial increase in current of normal polarity in said line circuit, a code transmitter at said station effective when operated to shunt said line circuit to increase the current in the portion thereof extending to the office, means for initially operating said code transmitter effective only when the station line relay is steadily energized to effect an initial operation of said line relay means, means controlled by said line relay means in response to said initial operation to reverse the polarity of the line current, means at the station responsive only to current of reverse polarity for continuing the operation of said code transmitter to transmit a multiple step code, a code receiver controlled by said line relay means selectively responsive to such code, and means controlled by said code receiver for restoring the polarity of the line current to normal at the end of such code.

13. In a remote control system, two line wires extending from a central office serially through a plurality of stations, a normally closed line circuit including in series, a source of current of reversible polarity at the office, said line wires, and a normally energized line relay responsive only to current of normal polarity at each station; line relay means at the office controlled over said line circuit but normally responsive only to a substantial increase in current of normal polarity in said line circuit, a code transmitter at each station effective when operated to close a shunt across said line circuit to increase the current in the portion thereof extending from such station to the office to operate said line relay means and to reduce the current in the remaining portion extending to more distant stations substantially to zero, means effective only when a station line relay is energized to operate the associated code transmitter for a predetermined time interval, means controlled by the line relay means in response to such initial operation to reverse the polarity of said current, means at each station responsive only to current of reverse polarity received within said predetermined time interval after the initiation of the associated transmitter effective to re-operate said transmitter repeatedly to transmit a multiple step

code, a code receiver at the office selectively responsive to each said code, and means controlled by said code receiver for restoring the polarity of the line current to normal at the end of each such code.

14. In a remote control system, two line wires extending from a control office serially through a plurality of stations, a code signaling circuit including said line wires and a source of current of reversible polarity at the office connected across said line wires in series with a line relay biased normally to its released position, a code transmitter at each station effective when operated to close a shunt connecting said line wires to effect the operation of the office line relay and to prevent the flow of current in the portion of said line circuit extending from such station to stations more distant from the office, means for initially operating each code transmitter for a predetermined time interval, means controlled by the office line relay in response to such initial operation to reverse the polarity of the current supplied to said line wires, means at each station responsive only to current of reverse polarity received within said predetermined time interval after the initiation of the associated transmitter to re-operate said transmitter repeatedly to transmit a multiple step code, a code receiver at the office selectively responsive to each such code, and means for restoring the polarity of the current supplied to the line wires to normal at the end of each such code.

15. In a remote control system, two line wires extending from a control office serially through a plurality of stations, a code signaling circuit including said line wires and a source of current of reversible polarity at the office connected across said line wires in series with a line relay biased normally to its released position, a code transmitter at each station effective when operated to close a shunt connecting said line wires to effect the operation of the office line relay and to prevent the flow of current in the portion of said line circuit extending from such station to stations more distant from the office, a line relay at each station responsive only to current of reverse polarity included in the shunt at such station, means for initially operating each code transmitter for a predetermined time interval, means controlled by the office line relay in response to such initial operation to reverse the polarity of the line current, means effective only if the station line relay picks up within said predetermined time interval after the initiation of the associated transmitter to re-operate said transmitter repeatedly to transmit a multiple step code, a code receiver at the office selectively responsive to each such code, and means for restoring the polarity of the line current to normal at the end of each such code.

16. In a remote control system, two line wires extending from a central office serially through a plurality of stations, a normally closed line circuit including, in series, a source of current of reversible polarity and a line relay biased normally to its released position at the office, said line wires, and a first line relay responsive only to current of normal polarity at each station, a code transmitter at each station effective when operated to close a shunt connecting said line wires to effect the operation of the office line relay and to release the line relay at each station more distant from the office; a second line relay at each station responsive only to

current of reverse polarity included in the shunt at such station, means at each station for initiating the operation of the code transmitter at such station provided the first line relay at such station is energized, means for maintaining each initiated code transmitter in its initial operated condition for a predetermined time interval, means responsive to the initial operation of the office line relay for reversing the polarity of the line current, means for repeatedly operating each initiated code transmitter effective only if the second line relay at the same station picks up within said predetermined time interval, to transmit a multiple step code, a code receiver at the office selectively responsive to each such code, and means for restoring the polarity of the line current to normal at the end of each such code.

17. In a remote control system, an office and a station connected by two line wires, a normally closed signaling circuit including said line wires and a source of current of reversible polarity at the office, a normally energized line relay at the station responsive only to current of normal polarity included in said circuit, a line relay at the office biased normally to its released position included in said circuit, a code transmitter effective when operated to connect said line wires together at the station to increase the current in said line wires to operate the office line relay, means effective only when the station line relay is energized for initiating the operation of said code transmitter, means controlled by the office line relay in response to such initial operation to reverse the polarity of the line current, means at the station responsive only to line current of reverse polarity of re-operating said transmitter repeatedly to transmit a multiple step code, a code receiver at the office selectively responsive to said code, and means for restoring the polarity of the line current to normal at the end of said code.

18. In a remote control system, an office and a station connected by two line wires, a line circuit including said line wires and a source of current of reversible polarity at said office, a line relay at the office biased normally to its released position included in said line circuit, a code transmitter effective when operated to connect said line wires together at the station to increase the current in said line circuit, means for initially operating said code transmitter, means at the office responsive to such initial operation to reverse the polarity of the line current, means at the station responsive only to current of reverse polarity for re-operating said transmitter repeatedly in accordance with a code to operate said office line relay, means controlled by said office line relay for selectively receiving said code, and means for restoring the polarity of the line current to normal at the end of such code.

19. In a remote control system, an office and a station connected by line wires; a normally closed line circuit including a source of current of reversible polarity, a normally closed transmitting contact, and a line relay biased normally to its released position at the office, said line wires, and a normally energized line relay responsive only to current of normal polarity at said station; means at the office for at times operating said transmitting contact repeatedly to open and close said line circuit in accordance with different multiple step codes, a code transmitter effective when operated to connect said line wires together at the stations to increase

the line current, means effective only when the station line relay is steadily energized for initially operating said code transmitter, means at the office responsive to such initial operation to reverse the polarity of the line current, means at the station responsive only to current of reverse polarity for re-operating said transmitter repeatedly in accordance with a code to govern said office line relay, means for restoring the polarity of the line current to normal at the end of such code, and code receivers controlled by the office and station line relays, respectively, responsive to said codes.

20. In combination, an office and a plurality of stations connected by two line wires arranged to provide a continuous metallic communication circuit from one end to the other, a remote control system for transmitting multiple impulse codes in both directions between said office and stations over said line wires while maintaining the continuity of said communication circuit comprising a source of current at the office normally supplying current to said line wires, a code transmitter at the office operable at times to periodically disconnect said source from the line wires to transmit codes to the stations, a code transmitter at each station operable when initiated to periodically connect the line wires together to prevent the flow of current to stations remote to the office while increasing the current supplied to the line wires to thereby transmit a code to the office, and means for initiating the operation of each code transmitter effective only when current is steadily being supplied over said line wires to the corresponding station.

21. In a remote control system, an office and a station connected by two line wires, a source of current of reversible polarity at the office connected to the line wires and normally supplying current of normal polarity to said station, a code transmitter at the office effective when initiated to periodically disconnect said source from the line wires to transmit multiple impulse codes to the station, means effective at times for initiating the office transmitter, a code transmitter at the station effective when current of reverse polarity is being supplied to the line wires to periodically increase said current to transmit multiple impulse codes to the office, and means for initiating said station transmitter comprising

means at the office responsive to the increase in line current due to an initial operation of said station transmitter occurring when the line wires are being supplied steadily with current of normal polarity to reverse the polarity of said current.

22. In combination, an office and a plurality of stations arranged in two groups connected by line wires, a normally closed line circuit including a source of current at the office, a normally closed transmitting contact, and said line wires; a biased polarized line relay at each station included in said line circuit, the line relays at the stations of one group being responsive only to current of the polarity normally supplied to said line circuit and those at the stations of the other group responsive only to current of the opposite polarity, means for operating said transmitting contact at times for controlling the line relays at the stations of said one group in accordance with a code of time spaced impulses all of normal polarity, means for at times temporarily disconnecting said transmitting contact and for then supplying to the line circuit a code of time spaced impulses of current from said source all of the reverse polarity to which the line relays at the stations of the other group are responsive, and a code receiver selectively controlled by each line relay.

23. In combination, an office and a plurality of stations connected by line wires providing a telephone circuit, a selector call system associated with said telephone circuit, a remote control system having a normally closed line circuit including said line wires and a source of current at said office, and code receivers at one or more of said stations, a code transmitter at said office operable only when said selector call system is inactive to control said line circuit to transmit codes from the office to said stations comprising time spaced current impulses all of the same polarity for selectively controlling said receivers, and means for operating said selective call system effective only when said code transmitter is inactive to transmit other codes to said stations comprising time spaced current impulses all of the opposite polarity, and selectors at certain of said stations controlled over said line circuit selectively responsive to said other codes.

GEORGE W. BAUGHMAN,
